his ATTORNEY

UNITED STATES PATENT OFFICE.

CHARLES R. CANNON, OF CLEVELAND, OHIO, ASSIGNOR TO THE BROWN HOISTING MACHINERY COMPANY, OF CLEVELAND, OHIO.

RUST-CLEANER.

976,342.

Specification of Letters Patent. Patented Nov. 22, 1910.

Application filed April 8, 1909. Serial No. 488,783.

To all whom it may concern:

Be it known that I, CHARLES R. CANNON, a citizen of the United States, residing at Cleveland, in the county of Cuyahoga and State of Ohio, have invented a new and useful Rust-Cleaner, as to which I hereby declare the following to be a full, clear, and exact description, reference being had to the accompanying drawings, made a part of the specification, wherein through the several figures the same parts are designated by the same letters.

My invention, so far as its greater use is concerned, relates more particularly to the cleaning, or removing, of rust that has developed on the surface of metallic material which has lain or been idle for some time, as in stock, or in partially finished structures. Its use, generally speaking however, as will occur upon consideration, is not confined to such employment, since the process is equally applicable to the cleaning of castings of various kinds, removing the spelter from brazings, barnacles from ships, and other like operations.

In modern steel construction, as in buildings, bridges, and heavy machinery, it is a usual practice to rivet, in place and together—generally at the shop—the contacting surfaces of the two pieces or parts that are to enter into the construction. Before this, however, said surfaces are given one or more coats of paint, but, because any rust-painted portions of the surfaces, will scale off and leave such portions unprotected against further oxygenation it is first necessary to clean the same thoroughly of rust. This has been done in various ways, as by hand-scraping, machine-brushing, or sand-blasts, each of which processes, however, is more or less unequal in effectiveness and involve an undesirable consumption of time and labor. After parts are riveted together, in the manner just referred to, they are, often, delivered at the site for erection or assemblage, and, before finally put in place, their remaining surfaces are rust-cleared and painted.

The object of my present invention is to afford a mechanical means of surface-cleaning that shall be convenient for handling, speedy in action, and thorough, uniform and economical in use and results.

In the drawings Figure 1 shows a machine embodying the invention, as a whole, when

in a working position with relation both to the work and the workman. Fig. 2, is an end view of the machine in the direction of the arrow in Fig. 1. Fig. 3 is a sectional view of the same on the lines y, y , of Fig. 2, with certain details omitted, and, Figs. 4, 5, 6 and 7 illustrate different positions the cleaning-blades will assume during operation.

The machine, itself, is broadly characterized as composed or made up of a hub-like drum or cylinder, of suitable material, either solid—or, hollow, as in the drawings, with the interior occupied by a resilient substance to reduce vibration or chatter,—and, an annular plate, about said cylinder, that carries at various exterior points thereon a transverse series of radially oscillatory blades or plates.

Pointing out the several constituent parts or features of the device, A represents the cylinder or collar, just referred to. This is hollow, and is counterbored and threaded at each end, and, has its outside diameter shortened, at such points, into annular recesses.

R is an interior closely fitted rubber filling or packing, with a central bore, lengthwise of the same, to receive the spindle L of a motor or other actuating medium.

For convenience or advantage in connecting said medium to the cleaner, the filling R is shorter, axially, than the circumscribing cylinder, to give room, within the latter, for a washer W, and, a following nut E on the forward or projecting end of the spindle L. Fitted in and around the annular recesses referred to above, are parallel and oppositely related pairs of circular side or dish-plates D, which are offset at their central portions and secured in their places by the nuts N one of which may be termed a head for said cylinder A that are screwed into the threaded counterbores, pointed out before, in the cylinder A. At intervals across and between said side or dish-plates D, near the circumference of the latter, are pins P, whose ends are shown as terminating in pivots p, p , that penetrate opposite bearing apertures in the plates D for the purpose, and, threaded upon said pins, through oval slots S in the same, are a series of blades B, of such number, in each case, as together to constitute a working fit on the pins. Such slots are given a longitudinal

dimension corresponding with the oscillatory movement or play that, in view of the conditions in a given case, it is desired or calculated such blades should have. The blades 5 of each series are separated, one from the other and from the plates D by intervening washers w. The blades, themselves, are flat, rectangular metallic plates, of slight relative thickness as compared with their other 10 dimensions. They are, preferably, slightly curved at their corners, or cutting points, and the latter, as well as the bearing points of the slots S, are likewise hardened or tempered to resist wear. The location of the 15 blade-receiving pins P is at a sufficient distance from the cylinder A as to give ample clearance to the blades when driven upwardly through their slots.

The motor or driving mechanism (shown 20 as M in Fig. 1) must be of high speed—as will be apparent—in order to insure an effective working of the device, a rapidity of as much as two thousand revolutions of the spindle L, per minute, being desirable. 25 This not only to give the cutting blades B, the momentum and force to strike and clear off the rust they encounter, but also, to insure that the centrifugal force engendered shall be adequate to maintain said blades 30 in a firm radial position on their pins throughout the entire revolution of the cylinder, and dish-plate to which they are attached.

The various parts pointed out having been 35 operatively connected together in their several places, as described, and, the spindle actuating-mechanism set in motion or started, the operation of the cleaner will be manifest. The centrifugal force thereby developed will keep the blades, of each series, 40 rigid, and upright with the inner ends of their slots S, in bearing against the pins P, at all stages of a revolution, except at the instant of contact with the surface to be 45 cleaned and while under the resulting opposite impetus such contact imparts.

Figs. 4, 5, 6 and 7 indicate the movement and action of the blades, under these latter conditions, and make clear a special utility 50 or advantage from said peculiar or special movements in the operation of the machine. Said figures show various relative positions of the blades to the cylinder A and plates D, during a revolution of the latter. The 55 same corner of a blade, in each of these figures, is denoted, respectively, by the letters a, b, c and d, the arrows t and t' pointing the direction or tendency of the blades B, and the plates D under the immediately impelling force in each case. In Fig. 4, said cylinder has brought the cutting corner a, into 60 contact with the surface of the work (indicated by C in these four figures, and in Fig. 1) while said cylinder is revolving in the direction of the arrow t. Said contact im-

parts to the blade a tendency to move, around the pivot or pin P, in an opposite direction, to the plates D, but, against the force both of its weight, and the centrifugal force that tends to carry the blade away from said pin, radially with respect to said cylinder and plate. The latter causes, when the moment of contact shown in Fig. 4 has passed, are sufficient to so far overcome the opposite force, or tendency in the direction of t, as to 75 carry the blade B backwardly, up and around its pin P, into the positions severally shown in Figs. 5 and 6, where (in Fig. 6) the center of gravity of the blade is off and, to the right of the pivotal or bearing point P, and, 80 the blade is, consequently, instantly whirled into a radial position, with respect to the cylinder A and plate D, and maintained in such relation throughout the revolution. A 85 desirable result is that the blade is completely reversed during each revolution, the diagonally opposite corner c (from a) becoming the next wearing or cutting edge, to be again reversed for the corner a, and so on until the work is finished. The center of 90 gravity of said blades, by such alternate reversals, is always kept at substantially the same point. When two opposite corners have, thus become worn down, it will be noted that by the special arrangement of my 95 machine shown, the different series of blades can be completely reversed, with respect to the spindle L, so that the diagonally opposite cutting edges b and d may be brought into action instead of the edges a and c. 100 This is readily effected by simply unscrewing the nut E and withdrawing the spindle from the packing R. Said packing is then slid within the cylinder A into the space before occupied by the nut and washer, N and 105 W, the machine turned end for end and replaced upon the spindle against the collar F thereon in the same manner, only reversed, as at first.

While I show, in this application, a specific machine, made up of definitely described parts or members, it is not intended in the broader claims herein, to limit my invention to the precise form of the same or of said parts, the cylinder and side or dish-plates, for instance, may not be separable from each other, but integral, and the latter may be in the shape of parallel ears or supports other than the annular disks shown, and, the exact form or dimensions of the 115 blades, as well as of the aperture corresponding with the slot S therein, may be varied without departing from said invention, in the sense referred to.

What I claim and desire to secure by Letters Patent, is:—

1. The combination of a central rotatory hub, oppositely arranged supports projecting radially from the ends thereof, transverse pins between and carried by said sup- 130

ports, together with a series of cutting blades loosely threaded upon said pins, through longitudinal slots therein, and suitable means for operatively connecting said hub with a rotatively actuating motor therefor, substantially as shown and described.

2. In a rust-cleaning device, the combination, with a cylindrical rotatory head, of oppositely arranged supports projecting radially therefrom at the ends thereof, transverse pins between and carried by said supports, and a series of oblong cutting blades threaded upon said pins through longitudinal apertures in said blades provided for the purpose, substantially as shown and described.

3. In a rust-cleaner, the combination with a central hub, or cylinder, of annular flanges or disk-like plates, projecting radially from each end thereof, transverse pins between and supported by said plates, together with a series of oblong cutting blades, threaded upon said pins, through slot-like apertures longitudinally of the same, substantially as shown and described.

4. In a rust-cleaning device, the combination with a rotatory head, of annular flanges or disk-like plates, projecting radially from and detachably connected to the ends thereof, transverse pins between and supported by said plates, together with a series of oblong cutting blades, loosely threaded upon said pins, through longitudinal slots or apertures in the same provided for the purpose, substantially as shown and described.

5. A rotary cleaning device comprising a pair of spaced side plates having means

whereby they may be mounted for rotation, a plurality of transverse pins arranged about the center of rotation of the side plates and at substantially equal distances from such center, and a plurality of blades mounted upon each pin and having the openings through which the pins pass larger than the diameter of the pins.

6. In combination in a cleaning device, a pair of spaced side plates having offset portions, a plurality of bearing pins between the side plates, blades thereupon, a central collar provided with a head at one end and fitting into the offset on one of the plates and a nut on the other end of the collar engaging the offset portion on the other plate.

7. A rotary cleaning device comprising a driving shaft, a rotary head or hub-like part secured thereto, a transverse series of cutting blades, and pins upon which said blades are radially pivoted at the periphery of the head through openings in said blades larger than the corresponding portions of the pins upon which the blades are mounted.

8. A rotary cleaning device comprising the combination of a rotary head or hub-like part and a series of cutting blades arranged transversely thereof and pivotally connected thereto by a common pin or journal that passes through openings in said blades larger than the corresponding portions of the pins.

CHARLES R. CANNON.

In presence of—

A. M. MERRYWEATHER,
L. P. LIPPS.
